UNITED STATES PATENT OFFICE.

LOUIS B. HARVEY, WALTER HORNBECK, AND BESSIE BISINGER, OF SACRAMENTO,
CALIFORNIA.

RETAINING-CLAMP FOR DEMOUNTABLE RIMS.

1,225,126.

Specification of Letters Patent.

Patented May 8, 1917.

Application filed April 20, 1916. Serial No. 92,402.

To all whom it may concern:

Be it known that we, LOUIS B. HARVEY, WALTER HORNBECK, and BESSIE BISINGER, citizens of the United States, residing at Sacramento, in the county of Sacramento, State of California, have invented certain new and useful Improvements in Retaining-Clamps for Demountable Rims; and we do declare the following to be a full, clear, and exact description of the same, reference being had to the accompanying drawings, and to the characters of reference made thereto, which form a part of this application.

This invention relates to improvements in retainers for holding demountable rims upon the fellys of wheels, the object of the invention being to produce a positive clamp for such rims which will evenly support the rim from all points and permit of a true and accurate placement of the rim upon the felly so that the wheel and rim will be substantially one equally supported unit when the rim is mounted on the felly and held by means of our improved clamp. We especially desire to provide a clamp which will avoid the now commonly used wedge retainers which, while fairly efficient for the purpose, have many disadvantages.

A further object of the invention is to produce a simple and inexpensive device and yet one which will be exceedingly effective for the purposes for which it is designed.

These objects we accomplish by means of such structure and relative arrangement of the parts as will fully appear by a perusal of the following specification and claims.

In the drawings similar characters of reference indicate corresponding parts in the several views.

Figure 1 is a side elevation of the vehicle wheel showing our improved clamping ring in position thereon.

Fig. 2 is a sectional view taken on a line X-X of Fig. 1.

Referring now more particularly to the characters of reference on the drawings the numeral 1 designates the hub of the wheel, 2 the spokes, and 3 the usual felly.

In providing our improved retaining member we first have a rim 4 shrunk onto the felly 3 in the usual manner, one side of the rim 4 being provided with a substantially V-shaped flange 5.

The numeral 6 designates the demountable rim or main structure which may be similar

to that used in my pending application for patent, Serial Number 63,269, filed November 24th, 1915, or any other of the various forms of demountable rims. For the purpose of coöperating with our improved clamping means the rim 6 would be provided on its under side with a pair of depending annular flanges or beadings 7 and 8. These flanges are so constructed and shaped that the flange 7, when the rim was mounted on the felly, would fit snugly into the V-shaped clamp 5, that is, the lower edge of the flange 7 would rest squarely against the lower side of the clamp 5 and the outer side of the flange 7 would rest squarely against the upper edge of the said clamp 5 so as to permit a perfect interlocking fit. Similarly the flange 8 is arranged to fit exactly into the V-shaped clamp 9 on an annular ring 10, having a plurality of slots 11 arranged to fit over retaining bolts 12 and be held in position by nuts 13.

When it is desired to remove the demountable rim 6 from off the felly, the nuts 13 are removed from the bolts 12. The ring 10 is then removed from the bolts which carries the clamping flange 9 away from the flange 8 and leaves the rim 6 free to be withdrawn from the felly.

When clamped onto the felly however, the flanges 7 and 8 fit very snugly into their retaining clamps 5 and 9 respectively and, as will be noted from Fig. 2, are supported both from the top and bottom so that there can be no possibility of the demountable rim shifting or creeping either circumferentially or vertically. By making the parts absolutely a true fit relative to each other there will be a positive coöperation between the same so that when the rim is mounted on the felly it will become a substantially unitary part thereof.

It will be readily seen that there is no wedging operation involved in our improved retainer but a true and accurate clamp is provided.

From the foregoing description it will readily be seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention.

the invention as defined by the appended claims.

Having thus described our invention what we claim as new and useful and desire to 5 secure by Letters Patent is:

1. A retaining clamp for automobile rims comprising the combination with a felly, a pair of V-shaped clamps carried by the felly, a rim, depending members on the rim, 10 such members being shaped to fit closely into the inner vertexes of the V-shaped clamps whereby the inner sides of the clamps will engage and support the outer sides and lower edges of the depending members.
- 15 2. A retaining clamp for demountable rims comprising the combination with a

felly, of a V-shaped flange projecting on one side of the felly, an annular ring removably mounted on the opposite side of the felly, a V-shaped flange similar to the first 20 named flange carried by said ring, a rim, projecting members on the rim, the edges of said projecting members fitting squarely against one side of the V-shaped flanges, the outer sides of said projecting members fitting squarely against the other sides of said 25 V-shaped flanges.

In testimony whereof we affix our signatures.

LOUIS B. HARVEY.
WALTER HORNBECK.
BESSIE BISINGER.
